CLAIM

An ornamental design for an overhead rack, as shown and described.

DESCRIPTION

FIG. 1 is a perspective view of an embodiment of an overhead rack.

FIG. 2 is a front elevational view of the overhead rack of FIG. 1.

FIG. 3 is rear elevational view of the overhead rack of FIG. 1.

FIG. 4 is a right side elevational view of the overhead rack of FIG. 1.

FIG. 5 is a left side elevational view of the overhead rack of FIG. 1.

FIG. 6 is top plan view of the overhead rack of FIG. 1.

FIG. 7 is a bottom plan view of the overhead rack of FIG. 1.

FIG. 8 is another embodiment of an overhead rack.

FIG. 9 is a front elevational view of the overhead rack of FIG. 8.

FIG. 10 is rear elevational view of the overhead rack of FIG. 8.

FIG. 11 is a right side elevational view of the overhead rack of FIG. 8.

FIG. 12 is a left side elevational view of the overhead rack of FIG. 8.

FIG. 13 is top plan view of the overhead rack of FIG. 8; and, FIG. 14 is a bottom plan view of the overhead rack of FIG. 8.

The elements shown in phantom, which are depicted as dot-dot-dot lines, are for illustrative purposes only and do not form part of the claimed design.
